PROCESS FOR THE REFINING OF
NAPHTHENIC ACIDS

Hugh Rogers Berry, Alton, Ill., assignor to Shell
Development Company, San Francisco, Calif.,
a corporation of Delaware

No Drawing. Application July 24, 1939.
Serial No. 286,238

5 Claims. (Cl. 260—514)

This invention relates to a method of refining crude naphthenic acid which contains various impurities including acidic organic sulfur compounds and neutral oils. More particularly, my invention relates to the improvement in refining crude naphthenic acid containing normally liquid organic acidic sulfur compounds, comprising the steps of heating said acids to elevated temperatures to decompose the sulfur compounds to neutral oils and gaseous sulfur compounds without effecting substantial decomposition of the naphthenic acids, removing the gases so formed, neutralizing the heat treated naphthenic acids with aqueous caustic alkali and extracting the resulting soap solution with a solvent for the unsaponifiable impurities.

Naphthenic acids are produced largely by extracting unrefined mineral oils containing the same with alkaline oil-insoluble liquids, and acidifying the extract to liberate extracted naphthenic acids. Naphthenic acids so obtained normally contain large proportions of impurities, chiefly sulfur compounds and neutral oils. These impurities greatly reduce the commercial value and usefulness of the naphthenic acids by reason of lowering their neutralization number and by forming dark, unstable, heavy metal salts, such as the lead salts. Presence of these impurities makes the salts unsuitable for use as paint driers, extreme pressure compounds in mineral lubricating oils, adhesives, and for many other purposes.

It is known that extracting an aqueous solution of the alkali metal salts of some crude naphthenic acid with a hydrocarbon oil may remove said impurities. However, I have found that crude naphthenic acids produced from certain mineral oils contain organic sulfur compounds having acidic properties so nearly resembling naphthenic acids in the matter of their acid properties that separation by neutralization with aqueous caustic alkali and extraction with a solvent for the unsaponifiable impurities is ineffective in removing said sulfur compounds. Moreover, as these organic acidic sulfur compounds are normally liquid and may have boiling ranges comparable to those of naphthenic acids, separation by distillation is not feasible.

It is a purpose of this invention to provide a single refining process, whereby from impure naphthenic acids containing said normally liquid acidic sulfur compounds, refined acids free from sulfur are produced.

It is another purpose to so improve the known methods of refining crude naphthenic acids by

solvent extraction of their aqueous soap solution, so as to make this method applicable to naphthenic acids containing organic acidic sulfur compounds not heretofore separable by simple means. Acids produced in accordance with my invention are capable of forming light-colored, heavy metal salts, and, in particular, lead salts which do not turn black upon preparation or standing.

The acidic sulfur compounds which are so difficult to remove from naphthenic acids containing them are believed to be sulfonic acids or other organic sulfur acids. I have found that these acids may be converted to normally gaseous sulfur compounds and neutral oils by heating them in a suitable vessel, such as a shell still, at temperatures of about 500 to 750° F. and preferably at temperatures from 600 to 700° F. without simultaneously decomposing the naphthenic acids if the time of heating is properly controlled. This heating may be carried out at substantially atmospheric or superatmospheric pressures. Pressures from 5 to 100 lbs. gauge are especially convenient. Therefore, I precede the known refining by solvent extraction of the soap solution with a heat treatment for a time sufficient to break down these acidic sulfur compounds. On the other hand, the time of heating must not be so long as to cause substantial evolution of CO₂. This can readily be achieved as naphthenic acids, in general, are sufficiently stable within the above temperature range to enable substantially complete decomposition of acidic organic sulfur compounds without decomposition of the naphthenic acids.

The proper time of heating may vary over a considerable range depending upon the exact temperature used. This is obvious from the known fact that the rate of thermal decomposition doubles approximately with every temperature increment of 22° F. At 685° F. the proper time is in the range of 5 to 30 minutes, and is more or less, depending on the temperature, in approximate accord with the above law governing the rate of thermal reactions.

The gas products formed during the heat treatment are separated from the naphthenic acid, either continuously or intermittently and may be analyzed immediately for CO₂. As soon as the CO₂ content of the waste vapors arises above a certain predetermined maximum the heating is discontinued and the still charge is allowed to cool. The resulting heat treated naphthenic acids are then neutralized with aqueous caustic alkali and extracted with a water immiscible sol-

vent for the unsaponifiable impurities under conditions to form two liquid layers which are then separated.

The most desirable solvent is a low sulfur 5 tor sweet hydrocarbon distillate, such as kerosene or mineral spirits. However, other light untreated hydrocarbon distillate oils, such as gas oil, naphtha, etc. might be employed. It is preferred, although not essential, to wash the soaps 10 with several small portions of the same or different solvents for the unsaponifiable residues and, if desired, after addition of further amounts of water to the aqueous soap solution.

After completed treatment as described above, 15 the clear soap solution is acidified with an aqueous solution of a suitable mineral acid which is stronger than naphthenic acids, such as sulfuric, hydrochloric acid, etc. to liberate the naphthenic acids from the soaps. Liberated 20 naphthenic acids are separated from the resulting aqueous layer and are washed with water to remove free mineral acid and salts. The washed naphthenic acids may now be used, if desired 25 after distillation for preparing the desired light colored, heavy metal salts, such as lead, cobalt, copper, etc., naphthenates, which are useful for many purposes. Further, if desired, the purified naphthenic acids may be fractionally distilled to produce several grades of the desired 30 naphthenates.

The following example further illustrates our process.

Example

A crude naphthenic acid containing about 30% 35 of sulfur acids and other sulfur compounds was placed in a still and heated under 35 lbs. gauge to a temperature of 685° F. The waste gases were vented through a watercooled condenser to condense escaping oil and naphthenic acids. 40 The temperature of 685° F. was maintained for about ten minutes, and as after the lapse of this time the formation of hydrogen sulfide had ceased, the still and its contents were allowed to cool. The recovered liquid distillate was combined with the still bottoms and the mixture 45 neutralized with the stoichiometric quantity of caustic soda. The resulting soap was dissolved in water, heated to about 200° F. to facilitate separation of neutral oils, and the separated 50 neutral oils were removed. The solution was then washed four times with a low sulfur naturally sweet kerosene to remove dark colored neutral oils formed while decomposing the sulfur compounds.

55 The purified soap solution was acidified with dilute sulfuric acid and the separated naphthenic acids recovered. These acids upon distillation yielded very light colored naphthenic acids that upon reacting with litharge formed light colored 60 lead naphthenates. Distilling the original naphthenic acids, without first subjecting them to the purification process, yielded naphthenic acids that upon reacting with litharge formed almost black colored lead naphthenates.

65 I claim as my invention:

1. In the process of refining crude naphthenic acid containing normally liquid acidic organic sulfur compounds by extracting an aqueous soap solution of said naphthenic acids with a water

immiscible solvent, the improvement comprising heating the crude naphthenic acid to a temperature of about 500° F. to 700° F. for a time sufficient to decompose a major portion of said organic sulfur compounds thereby converting said 5 organic sulfur compounds to neutral oils and normally gaseous sulfur compounds and to produce heat treated naphthenic acids, separating the said gaseous compounds from the heat treated acids and dissolving said acids in aqueous caustic 10 alkali to form said soap solution.

2. In the process of refining crude naphthenic acid containing normally liquid acidic organic sulfur compounds by extracting an aqueous soap solution of said naphthenic acids with a water immiscible solvent for unsaponifiable impurities with which crude naphthenic acids are usually associated, the improvement comprising heating the crude naphthenic acid to a temperature of about 500° F. to 750° F. and under superatmospheric pressure for a time sufficient to decompose the organic acidic sulfur compounds to form normally gaseous sulfur compounds and neutral oils and insufficient to liberate substantial amounts of CO₂ and separating the said gaseous 20 compounds from the heat treated acids and dissolving said acids in aqueous caustic alkali to form said soap solution.

3. In the process of preparing purified naphthenic acid by extracting an aqueous alkaline solution of crude naphthenic acids containing normally liquid acidic organic sulfur compounds by extracting an aqueous soap solution of said naphthenic acids with a volatile petroleum distillate, the improvement comprising heating the crude 3 naphthenic acid to a temperature of about 600° F. to 700° F. and under a pressure of about 5 to 100 pounds until gaseous sulfur compounds are no longer evolved and separating said sulfur compounds from the heat treated acids and dissolving said acids in aqueous caustic alkali to form said soap solution.

4. In the process of preparing purified naphthenic acid by extracting an aqueous alkaline solution of crude naphthenic acids containing normally liquid acidic organic sulfur compounds by extracting an aqueous soap solution of said naphthenic acids with a volatile petroleum distillate, the improvement comprising heating the crude naphthenic acid to a temperature of about 5 600° F. to 700° F. for 5 to 30 minutes and under a pressure of 5 to 100 pounds and separating the gaseous sulfur compounds formed from the heat treated acids and dissolving said acids in aqueous caustic alkali to form said soap solution.

5. In the process of preparing purified naphthenic acid by extracting an aqueous alkaline solution of crude naphthenic acids containing normally liquid acidic organic sulfur compounds by extracting an aqueous soap solution of said naphthenic acids with a volatile petroleum distillate, the improvement comprising heating the crude naphthenic acid to a temperature of about 6 685° F. for about 10 minutes and under a pressure of 35 pounds and separating the gaseous sulfur compounds formed from the heat treated acids and dissolving said acids in aqueous caustic alkali to form said soap solution.

HUGH ROGERS BERRY,
